US00D941287S

(12) **United States Design Patent** (10) Patent No.: **US D941,287 S**
(45) Date of Patent: **** Jan. 18, 2022**

(54) **LAPTOP COMPUTER**

(71) Applicant: **Lenovo (Beijing) Co., Ltd.**, Beijing (CN)

(72) Inventors: **Brian Leonard**, Beijing (CN);
Chih-kai Huang, Beijing (CN);
Truong Cuong, Beijing (CN)

(73) Assignee: **Lenovo (Beijing) Co., Ltd.**, Beijing (CN)

(**) Term: **15 Years**

(21) Appl. No.: **35/510,425**

(22) Filed: **Jun. 29, 2020**

(80) **Hague Agreement Data**

Int. Filing Date: **Jun. 29, 2020**

Int. Reg. No.: **DM/210342**

Int. Reg. Date: **Jun. 29, 2020**

Int. Reg. Pub. Date: **Sep. 25, 2020**

(30) **Foreign Application Priority Data**

Dec. 31, 2019 (CN) 201930749606.9

(51) **LOC (13) Cl.** **14-02**

(52) **U.S. Cl.**

USPC **D14/315**
